DESIGN FOR A PARKING METER

Lyle H. Huntoon, Los Angeles, Calif., assignor to
Welcome Meter Company, Pasadena, Calif., a
corporation of California

Application October 20, 1936, Serial No. 65,388

Term of patent 3½ years

To all whom it may concern:

Be it known that I, Lyle H. Huntoon, a citizen of the United States, and a resident of the city of Los Angeles, in the county of Los Angeles, and State of California, have invented a new, original, and ornamental Design for Parking Meter, of which the following is a specification, reference being had to the accompanying drawing, forming part thereof, in which:

Figure 1 is a side elevation of a parking meter showing my new design;

Fig. 2 is a front elevation thereof; and

Fig. 3 is a sectional view thereof, as seen on line 3—3 of Fig. 1.

The dominant features of the design are the form of the dial adjacent the top of the device and visible through a window; and the configuration of the top which is translucent and through which a light may be seen.

I claim.

The ornamental design for a parking meter substantially as shown and described.

LYLE H. HUNTOON.
